Primary Examiner — Sanjeev Paul

(57) **CLAIM**

We claim the ornamental design for a heads-up display mount, as shown and described.

DESCRIPTION

FIG. 1 is a top perspective view of a heads-up display mount;

FIG. 2 is a bottom perspective view thereof;

FIG. 3 is a bottom perspective view thereof; and,

FIG. 4 is a front view thereof.

The broken lines shown in the drawings represent portions of the heads-up display mount that form no part of the claimed design.
